UNITED STATES PATENT OFFICE

124,964

DESIGN FOR A DUPLICATOR

Raymond C. Casanov, Chicago, Ill., assignor to
L. C. Casanov, Chicago, Ill.

Application September 16, 1940, Serial No. 95,123

Term of patent 3½ years

To all whom it may concern:

Be it known that I, Raymond C. Casanov, a citizen of the United States and a resident of Chicago, in the county of Cook and State of Illinois, have invented a new, original, and ornamental Design for a Duplicator, of which the following is a specification, reference being had to the accompanying drawing, forming a part thereof, and in which:

Fig. 1 is a perspective view of a duplicator showing my new design;

Fig. 2 is an end perspective view of the same as seen from the right of Fig. 1;

Fig. 3 is a side elevational view of the same showing the long side not seen in Fig. 1; and

Fig. 4 is an end elevational view of the same as seen from the left of Fig. 1.

I claim:

The ornamental design for a duplicator, as shown.

RAYMOND C. CASANOV.
